PACKAGING TRAY FOR CONTAINING AND DISPENSING RAZOR BLADE UNITS

Christopher J. Hood, Tolworth, England, assignor to
Wilkinson Sword Limited

Filed May 20, 1974, Ser. No. 471,205

Claims priority, application Great Britain Nov. 29, 1973

Term of patent 14 years

Int. Cl. D9—03

U.S. Cl. D9—189

FIG. 1.

FIG. 2.

FIG. 3.

FIG. 4.

FIG. 5

FIG. 6.

FIG. 7.

FIG. 1 is a perspective view of a packaging tray for containing and dispensing razor blade units, showing my new design;

FIG. 2 is a side elevational view;

FIG. 3 is a side elevational view showing the side opposite that seen in FIG. 2;

FIG. 4 is an end elevational view;

FIG. 5 is an end elevational view showing the end opposite that seen in FIG. 4;

FIG. 6 is a top plan view; and

FIG. 7 is a bottom plan view thereof.

I claim:

The ornamental design for a packaging tray for containing and dispensing razor blade units, as shown.
